APPARATUS FOR PREPARING AND DISPENSING ADHESIVE COATED TAPE

George A. Gerard, Roselle, N. J.

Application June 2, 1950, Serial No. 165,711

8 Claims. (Cl. 118—43)

1

This invention relates to apparatus for preparing and dispensing adhesive coated tape, and more particularly to the preparation of pressure sensitive tape such as may now be found in common use.

The primary object of the invention is to coat a strip of tape with a pressure sensitive substance as the tape is being withdrawn from the device for use.

Another object is to avoid deterioration of the pressure sensitive coating through age, and to supply freshly coated tape in accordance with the demand.

A further object is to support in a position for immediate use a length of properly dried pressure sensitive tape, and to render readily accessible the exact amount of tape required.

The above and other objects may be attained by employing this invention which embodies among its features means for supporting a roll of tape to which adhesive is to be applied, means supported near the roll supporting means for applying a layer of adhesive to one side of the tape as it leaves the roll of tape, tape guides supported in spaced relation around the roll supporting and adhesive applying means for engaging the untreated side of the tape to which adhesive has been applied and holding said tape in spaced convolutions around the roll supporting and the adhesive applying means, and a dispenser supported in spaced relation to the outer convolution of tape on the side thereof remote from the other convolutions for engaging a portion of the treated side of the outer convolution of tape and holding it into position to be manually extracted from the apparatus.

Other features include means for regulating the resistance of the roll of tape to rotary movement, a reservoir for containing adhesive removably mounted adjacent the roll supporting means, a cylinder carried by the reservoir and extending thereto for emersion in the adhesive contained therein, a porous surface on the cylinder for collecting the adhesive as the cylinder rotates in the reservoir, and means to remove excess adhesive from the surface of the cylinder to prevent an excess deposit of adhesive on the tape as it moves with the cylinder.

Other features include a group of spaced tape guides around which passes adhesive treated tape in spaced convolutions, each guide comprising an arcuate body having spaced parallel arcuate flanges extending outwardly from opposite side edges thereof, said flanges having radial slots extending therethrough and opening through the

2

outer edges thereof, the slots in one flange registering with those in the other flange, a roller for each slot, trunnions on opposite ends of the rollers and entering registering slots, and a retainer carried by each flange along the edge thereof remote from the arcuate body for closing the ends of the slots and retaining the trunnions therein.

In the drawings:

Figure 1 is a side view of apparatus for preparing and dispensing adhesive coated tape constructed in accordance with this invention with the cover plate removed,

Figure 2 is an end view of the dispensing end of the device,

Figure 3 is a vertical sectional view taken substantially along the line 3—3 of Figure 1,

Figure 4 is a fragmentary view of the dispensing end of the device with the cover plate, the tape guides, and the adhesive applying apparatus removed,

Figure 5 is a fragmentary rear side view of the device,

Figure 6 is a detailed view partly in section on an enlarged scale of one of the tape guides,

Figure 7 is a sectional view taken substantially along the line 7—7 of Figure 6, and

Figure 8 is an enlarged fragmentary sectional view taken substantially along the line 8—8 of Figure 3.

Referring to the drawings in detail this improved dispenser includes a substantially rectangular plate 10 which carries at its perimeter an outstanding laterally projecting wall 12, and carried on the face of the plate 10 from which the wall 12 extends and spaced inwardly from said wall 12 are similar outstanding walls 14, 16, 18 and 20, which lie in spaced parallel relation to the wall 12 and cooperate therewith in forming a substantially rectangular drying chamber 22, and an inner chamber 24. Carried by the plate 10 and projecting therefrom on the side opposite the walls 12, 14, 16, 18 and 20 is a boss 26 having an axial opening 28 extending therethrough, the purpose of which will be more fully hereinafter described. Formed in the plate 10 near the lower right hand corner thereof when viewed as in Figures 1 and 4, is an irregularly shaped opening 30 for the reception of the reservoir which will be more fully hereinafter described. Projecting inwardly from the wall 10 adjacent each corner thereof is a group of pads 32 upon which the tape guides are mounted. A similar pad 34 is carried by the wall 10 adjacent the wall 12 at the dispensing end of the device, and projecting outwardly from the wall 12 inter-

mediate the ends thereof at the dispensing end of the device is a bracket 36 having an upwardly opening recess 38 extending transversally therethrough which cooperates with the bracket 36 in forming a dispenser 40 which supports a portion of the treated tape in a position to be grasped by the fingers of the user preparatory to extracting a length of tape from the device. The wall 12 in the vicinity of the dispenser 40 is provided with an opening 42 through which the tape is extracted from the interior of the device. A wall section 20' is carried by the body 10 between the wall 20 and the dispenser 40, and is offset from the wall 20 to form a passage 20b as will be readily understood upon reference to Figures 1 and 4. Each of the wall sections 14, 16, 18 and 20 is provided with an inwardly extending lug 44, and each lug is provided with an internally screw threaded opening 46 for the reception of attaching screws 48 (Fig. 2) by which a cover plate designated generally 50 is detachably connected to the device. Extending through the plate 50 and opening into the chamber 22 at the side thereof remote from the dispenser 40 is an opening 52 through which a blast of air from a suitable air heater (not shown) may enter the chamber 22 in order to aid in drying adhesive which has been applied to the tape before it reaches the dispenser 40.

To cover plate 50 above referred to comprises a substantially rectangular body 54 having a relatively large opening 56 extending therethrough which aligns axially with the opening 28, to facilitate the mounting and demounting of a roll of tape on the tape supporting drum to be more fully hereinafter described. This rectangular plate 54 is also provided with an elongated opening 58 which when the plate is in place registers with the irregular opening 30 in the plate 10 to accommodate the adhesive applying apparatus previously referred to.

Fixed in the opening 28 in the boss 26 is a stud 60 which projects into the chamber 24 and through the opening 56 and is provided adjacent its end remote from the boss 26 with external screw threads 62 on which knurled hand nuts 64 and 66 are mounted. Supported on the stud 60 between the nuts 64 and 66 and the wall or body 10 are friction discs 68 and 70. A pressure disc 72 surrounds the stud 60 between the friction disc 70 and the thumb nut 64, and mounted for rotation on the stud 66 between the friction discs 68 and 70 is a drum 74 upon which is mounted a roll of tape T to be treated. It will thus be seen that by turning the thumb nuts 64 and 66 on the stud 60, the friction discs 68 and 70 will exert controlled pressure on opposite sides of the drum 74 so that its resistance to turning may be governed.

Extending through the opening 30 in the body 10 is the reservoir 78 of the adhesive applying unit designated generally 78, and carried by the reservoir are attaching flanges 80 which bear against the body 10 adjacent the side thereof remote from the wall 12, and extending through these attaching flanges and into threaded openings in the body 10 are screws 82 by which the adhesive applying unit 78 is removably mounted on the body 10. Formed on the reservoir 46 of the adhesive applying unit 78 is an upstanding boss 84 having an opening 86 extending therethrough in which a shaft 88 is mounted to rotate. This shaft extends through the opening 30 into the chamber 24 and carries on the end within the chamber a

cylinder 90 which projects into the reservoir and has its lower edge submerged in adhesive contained in the reservoir. In the preferred form of the invention the cylinder 90 is provided on its circumference with suitable indentations 92 which serve to collect adhesive and carry it upwardly as the cylinder rotates. A suitable hand wheel 94 is fixed to the shaft 88 at the end thereof remote from the cylinder 90 which serves in conjunction with a shoulder 96 formed on the shaft 88 to hold the shaft in proper position in the boss 84. Extending upwardly from the reservoir 78 adjacent opposite ends thereof are bosses 98 and 100 in which horizontally extending studs 102 and 104 are secured. These studs 102 and 104 lie along axes which lie parallel with the axis of the shaft 88, and project through the irregular opening 30 into the chamber 24 as will be readily understood upon reference to Figure 1. Mounted for rotation on the stud 100 is a guide roller 104, and a similar guide roller 106 is mounted for rotation on the stud 102, both rollers 104 and 106 being located within the chamber 24 so that tape T leaving the roll pass beneath the roller 104, thence over the cylinder 90 and beneath the roller 106. In this way one side of the tape T becomes coated with the adhesive carried by the screen 92 on the cylinder 90. Secured to the under side of the top wall of the reservoir 78 near the upstanding boss 84 is a spiral spring 108 which projects into the chamber 24 and carries at its end within the chamber a scraper blade 110 which engages the outer surface of the screen band 92 to remove excess adhesive therefrom.

From the foregoing it will be seen that tape T leaving the roll which is mounted on the drum 74 and passing through the adhesive applying unit 78 will by reason of the location of the roller 106 of said unit be delivered beneath the lower end of the wall 20, through the passage 20b into the chamber 22.

In order to support the tape T in spaced convolutions in the chamber 22 I provide adjacent each corner of the rectangular body 10 a group of spaced guides each designated generally 112. Each such guide comprises a substantially arcuate body 114 which carries along opposite side edges outwardly extending arcuate flanges 116. These flanges are provided with circumferentially spaced radial slots 118 which open outwardly through the edges of the flanges as will be readily understood upon reference to Figure 6. The slots in opposite flanges register with one another to receive the trunnions 120 of guide rollers 122, and extending around the outer edges of the flanges 116 are retaining members 124 which extend across and close the open ends of the slots 118 to prevent the trunnions 120 of the rollers 122 from leaving their respective slots 118. A suitable triangular lug 126 is carried by the body 114 and extending through said lug is a countersunk opening 128 for the reception of a suitable attaching screw 130 by which the guide 112 is mounted on a boss 32. By mounting the tape guides 112 as indicated in Figure 1 in the chamber 22, it will be seen that tape leaving the roller 106 and passing upwardly through the passage 20b will be guided by the tape guides 112 in a series of spaced convolutions through the chamber 22 and around the chamber 24 and the drum 74 and adhesive applying unit 78. Leaving the outermost tape guide 112 at the lower right

hand corner of the chamber 22, the tape T is carried upwardly over a tape guide designated generally 132, the upper delivery end of which lies in a plane with the top of the dispenser 40 so that the tape issuing from the tape guide 132 will bridge the recess 38 to enable the user to grip the tape by passing his fingers through the recess. The tape guide 132 is identical in construction with the tape guides 112 with the exception that the peripheries of the rolls contained in the tape guide 132 are knurled.

In use it will be understood that a roll of uncoated tape is mounted on the drum 74 by passing it through the opening 56 in the cover plate 50. The tape is then threaded from the roll downwardly beneath the roller 104 and over the cylinder 90 from whence it is passed beneath the roller 106 and upwardly and through the passage 20b to the innermost tape guide 112 in the upper right hand corner of the device when viewed as in Figure 1. The tape is then passed horizontally over the tape guide 112 at the upper left hand corner and thence downwardly through the chamber 22 around the tape guide at the lower left hand corner of the device from whence it passes horizontally to the innermost tape guide 112 at the lower right hand corner of the device from whence it passes upwardly over the intermediate tape guide 112 in the upper right hand corner of the device. The tape continues on around the tape guides as previously described until it reaches the outermost tape guide 112 in the lower right hand corner of the device from whence it passes upwardly and over the tape guide 132 from which it is delivered horizontally on substantially a level with the upper edge of the dispenser 40 so as to bridge the opening or recess 38 in the bracket 36. If so desired a suitable serrated cutting knife 134 may be attached to the dispenser 40 as suggested in Figure 1 so that when a user passes his finger through the recess 38 beneath the horizontally extending portion of the tape supported by the dispenser and grips the tape to pull it out of the apparatus, he may by moving the tape downwardly against the serrated edge of the blade 134 sever the length of tape desired from the remainder of the tape and at the same time cause the tape to contact the upper surface of the dispenser 40 so that it will be held for a repeat operation. The indentations 92 encircling a drum 90 assure adequate supply of adhesive to the tape and the scraper 110 serves to prevent an excess amount of adhesive from being delivered to the tape. Should it be so desired a suitable air delivery and heating unit may be used in conjunction with the device and so coupled thereto as to deliver air through the opening 52 into the drying chamber 22, and since the treated tape is suspended in a series of spaced convolutions within the drying chamber 22 it is evident that adequate circulation of air across the coated side of the tape may be had so as to deliver tape to the dispenser with the adhesive in proper condition for use. Owing to the fact that the tape in the roll is devoid of an adhesive coating, it is evident that serious loss through age of the roll tape cannot result.

While in the foregoing there has been shown and described the preferred form of this invention, it is to be understood that minor changes in details of construction, combination and arrangement of parts may be resorted to without

departing from the spirit and scope of the invention as claimed.

I claim:

1. In apparatus for preparing and dispensing adhesive treated tape, means for supporting a roll of tape to which adhesive is to be applied, means supported near the roll supporting means for applying a layer of adhesive to one side of the tape as it leaves the roll of tape, tape guides supported in spaced relation around the roll supporting and adhesive applying means for engaging the untreated side of the tape to which adhesive has been applied and holding said tape in spaced convolutions around the roll supporting and the adhesive applying means, and a dispenser supported in spaced relation to the outer convolution of tape on the side thereof remote from the other convolutions for engaging a portion of the treated side of the outer convolution of tape and holding it in position to be manually extracted from the apparatus.
2. In apparatus for preparing and dispensing adhesive treated tape, means for supporting a roll of tape to which adhesive is to be applied, an adhesive carrying cylinder mounted for rotation adjacent the roll supporting means over which tape from a roll of tape on the roll supporting means passes after it leaves the roll and which applies adhesive to one side of the tape, spaced tape guides supported around the roll supporting means and cylinder in spaced relation thereto for engaging untreated side of the tape after it leaves the cylinder and holding it in spaced convolutions around the cylinder and the roll supporting means, and a dispenser supported in spaced relation to the outer convolution of tape on the side thereof remote from the other convolution for engaging a portion of the treated side of the outer convolution of tape and holding it in position for manual extraction from the apparatus.

3. In apparatus for preparing and dispensing adhesive coated tape, a support, a tape roll supporting drum carried by the support for rotation about a horizontal axis, an adhesive carrying cylinder carried by the support for rotation about an axis which lies parallel with the horizontal axis, said cylinder engaging the tape and applying adhesive to one side thereof, spaced tape guides carried by the support in spaced relation to the drum and to the cylinder upon which treated tape after leaving the cylinder is supported in spaced convolutions with its treated side outwardly and a treated tape dispenser carried by the support in spaced relation to the outer convolution of tape for engaging a portion of the treated side of the outer convolution of tape and holding it in position for manual extraction from the apparatus.

4. In apparatus for preparing and dispensing adhesive coated tape, a support, a tape roll supporting drum carried by the support for rotation about a horizontal axis, an adhesive carrying cylinder carried by the support for rotation about an axis which lies parallel with the horizontal axis, said cylinder engaging the tape and applying adhesive to one side thereof, spaced tape guides carried by the support in spaced relation to the drum and to the cylinder upon which treated tape after leaving the cylinder is supported in spaced convolutions with its treated side outwardly, a wall carried by the support and extending around the perimeter thereof in spaced

relation to the outer convolution of treated tape, and a dispenser carried by the wall for engaging the treated side of a portion of the outer convolution of tape and holding it in a position for manual extraction from the apparatus.

5. In apparatus for preparing and dispensing adhesive treated tape, a rectangular support, a tape roll carrying drum carried by the support for rotation about a horizontal axis, said support having an opening extending therethrough near the drum, adhesive applying apparatus extending through said opening, said apparatus having an adhesive carrying cylinder over which passes one side of the tape from a roll of tape carried by the drum, a group of tape guides carried by the support adjacent each corner thereof for engaging the untreated side of the tape after it leaves the cylinder and supporting said tape in spaced convolutions around the drum and the cylinder, and a dispenser mounted on the support adjacent the outermost convolution for engaging a portion of the treated side of the outer convolution of tape and holding it in a position for manual extraction from the apparatus.

6. In apparatus for preparing and dispensing adhesive treated tape, a rectangular support, a tape roll carrying drum carried by the support for rotation about a horizontal axis, said support having an opening extending therethrough near the drum, adhesive applying apparatus extending through said opening, said apparatus having an adhesive carrying cylinder over which passes one side of the tape from a roll of tape carried by the drum, a group of tape guides carried by the support adjacent each corner thereof for engaging the untreated side of the tape after it leaves the cylinder and supporting said tape in spaced convolutions around the drum and the cylinder, a wall carried by the support adjacent the perimeter thereof in spaced relation to the outer convolution of tape, and a dispenser carried by said wall for engaging a portion of the treated side of the outer convolution of tape and holding it in position to be manually extracted from the apparatus.

7. A mechanism for making pressure sensitive adhesive tape by applying a pressure sensitive rubber-like adhesive thereto in a central rectan-

5 gular chamber followed by drying and dispensing in and from an encircling outside rectangular chamber which comprises providing a double casting having a first coating central chamber and a second outside drying chamber enclosing said first chamber, a roll of tape supported in said first chamber, a transverse shaft for receiving said roll of tape and a roller coater also in said first chamber for applying a rubber adhesive coating to one side of said tape as it is unrolled from said roll of tape and guides including a plurality of spaced guide rollers at the corners of the outside chamber, said rollers contacting and carrying the said tape on its uncoated side and guiding the coated tape while the same is dried and a dispenser at one side of said casing to dispense the dried coated tape, said outside chamber having openings at opposite ends thereof to permit the blast of hot air to be passed through the outside chamber to dry said coating while said tape is passing through said second chamber over said rollers.
